DESIGN FOR A LIPSTICK HOLDER

Ethel Franklin, New York, N. Y., assignor to Charles of the Ritz, Inc., New York, N. Y., a corporation of Delaware

Application May 13, 1947, Serial No. 139,013

Term of patent 14 years

(Cl. D86—10)

To all whom it may concern:

Be it known that I, Ethel Franklin, a citizen of the United States, residing at 445 West 23rd Street, New York city, in the county of New York and State of New York, have invented a new, original, and ornamental Design for a Lipstick Holder, of which the following is a specification, reference being had to the accompanying drawing, forming part thereof.

The figure is a perspective view of a lipstick holder showing my new design, the holder presenting the same appearance shown when viewed from the undisclosed areas.

I claim:

The ornamental design for a lipstick holder, substantially as shown and described.

ETHEL FRANKLIN.
